UNITED STATES PATENT OFFICE.

JAMES I. MONNETT AND HERBERT S. BLYNT, OF YALE, OKLAHOMA.

CUSHION SHOE-HEEL.

1,380,825.

Specification of Letters Patent. Patented June 7, 1921.

Application filed February 18, 1919. Serial No. 277,852.

To all whom it may concern:

Be it known that we, JAMES I. MONNETT and HERBERT S. BLYNT, citizens of the United States of America, residing at Yale, 5 in the county of Payne and State of Oklahoma, have invented certain new and useful Improvements in Cushion Shoe-Heels, of which the following is a specification.

This invention relates to certain new and 10 useful improvements in cushion shoe heels and has particular reference to that type of cushion heel provided with anti-slipping means.

The primary objects of this invention are 15 to provide a rubber heel so constructed as to give increased wear, a cushion effect and a non-slipping effect.

With the above general objects in view and others that will become apparent as the 20 nature of the invention is better understood, the same consists in the novel form, combination and arrangement of parts herein-after more fully described, shown in the accompanying drawing and claimed.

25 In the accompanying drawing, in which like reference characters designate corresponding parts throughout the several views,

Figure 1 is a fragmentary view of the heel portion of a shoe partly broken away and 30 illustrating the present invention in operative position,

Fig. 2 is a bottom plan view of the device shown in Fig. 1,

Fig. 3 is an elevational view of the metallic plate and thimbles forming part of the 35 invention,

Fig. 4 is an elevational view of the cushion plate or lift forming the heel proper, and

Fig. 5 is a perspective view of one of the 40 plugs.

In carrying out the objects of this invention, we provide a plate or lift 5 of elastic material such as rubber or rubber composition having a plurality of transverse openings therethrough as at 6 which are surrounded at the wearing face of the lift by annular beads or ribs 7. It will be understood that the lift 5 is shaped in accordance with the usual form of a shoe heel and the 45 upper face of the same is provided with a recess as at 8 of a form to snugly receive the metallic plate 9 preferably of the general form of the lift 5 and of slightly smaller dimensions than the latter. The plate 9 may

50 be made out of any suitable metal such as brass, copper, steel or aluminum and may

be formed by stamping, casting or the like. Rigid with and extending from one face of the plate 9 are a plurality of tubular studs or thimbles 10 so arranged upon the plate 9 as to enter the openings 6 of the lift 5 as clearly shown in Fig. 1 to extend to a point adjacent the wearing surface of said lift. The thimbles 10 are made of such diameter as to require the same to be forced into the 65 openings 6 and thereby insure against separation of the members 5 and 9.

The plate 9 is placed in the recess 8 so as to obscure said plate from view when attached to a shoe and thus give the latter a 70 neat appearance. In order to attach the present heel to a shoe, the plate 9 is provided with suitable perforations preferably centrally of the thimbles 10 as at 11 adapted to receive fasteners such as screws 12 which 75 are turned into the leather heel lift 13 of the shoe A, thus securely fastening the cushion heel in place.

In order to enhance the anti-slipping, 80 wearing and cushion qualities of the present heel, suitable rubber or cork plugs 14 are provided substantially of the same length as the thimbles 10 and of a diameter to insure retention of the same in the thimbles by friction when so disposed. The plugs 14 are, 85 of course, placed in the thimbles 10 after the lift 5 and plate 9 have been assembled and fastened to the shoe by means of screws 12 and it is obvious that said plugs can be renewed from time to time as made necessary by damage or wear. It is obvious that 90 these plugs may be made out of not only cork or rubber but also felt, fiber, aluminum or leather, and when the same are inserted in the thimbles, the heel is made moisture 95 proof or substantially so by preventing moisture from passing through the perforations which receive the screws 12.

It will be seen that the circular free ends or edges of the thimbles 10 form rings of 100 contact with the ground whereby a non-slipping effect is had by a means which increase the wearing quality of the heel although allowing a sufficient cushion effect by reason of the ribs 7 and the rubber or 105 other elastic lift 5 together with plugs 14.

From the foregoing description, it is believed that the construction and advantages of the present invention will be readily understood by those skilled in the art and 110 while the form of the invention herein shown and described is what is believed to

be the preferable embodiment thereof, it is nevertheless to be understood that minor changes may be made in the form, combination and arrangement of parts without departing from the spirit and scope of the invention as claimed.

What we claim as new is:—

A cushion heel, comprising a resilient lift having transverse openings therethrough 10 and a recess in the upper face thereof, a flat plate of slightly smaller dimensions than the lift and snugly fitting in said recess, a plurality of cylindrical metallic thimbles rigid with said plate and extending through

said openings in frictional contact with the 15 walls of the latter, resilient plugs in said thimbles and extending slightly beyond the free ends of the latter, and screws extending through the plate centrally of the thimbles to secure the heel to the heel portion 20 of a shoe, said screws being independent of the plugs whereby the plugs may be removed and inserted without removal of the heel as a whole.

In testimony whereof we affix our signatures. 25

JAMES I. MONNETT.
HERBERT S. BLYNT.
